UNITED STATES PATENT OFFICE.

OTTO LIEBKNECHT, OF FRANKFORT-ON-THE-MAIN, GERMANY, ASSIGNOR TO THE ROESSLER & HASSLACHER CHEMICAL COMPANY, OF NEW YORK, N. Y., A CORPORATION OF NEW YORK.

PROCESS OF MAKING ALKALI PERBORATES.

1,253,061.

Specification of Letters Patent.

Patented Jan. 8, 1918.

No Drawing.

Application filed May 31, 1916. Serial No. 100,982.

To all whom it may concern:

Be it known that I, OTTO LIEBKNECHT, a subject of the German Emperor, and resident of Frankfort-on-the-Main, Germany, have invented certain new and useful Improvements in Processes of Making Alkali Perborates, of which the following is a specification.

This process relates to the art of making perborates and it particularly relates to a process for the electrolytic production of alkali perborate by an electrolytic process.

In U. S. patent application, Serial No. 70,592, filed January 6, 1916, I have described the manufacture of alkali perborate consisting in a double decomposition of a solution of electrolytically produced alkali percarbonate with a solution of an alkali borate and particularly a process of making sodium perborate consisting in electrolyzing a solution of an alkali carbonate and a sodium borate.

According to my application mentioned above sodium perborate is produced easily, if the work is carried out in the presence of a solid salt, preferably in the presence of solid perborate of sodium.

It has been found during the manufacture of perborate of sodium by the electrolysis of an alkali-carbonate solution containing an alkali borate, that the yield of perborate per unit quantity of current is considerably lowered by the reducing action at the cathode.

The discovery has now been made that it is possible to increase the yield to a considerable extent without any disturbing action, by adding to the electrolyte chromic acid or such chromates, the base of which does not have a decomposing effect on alkali perborate solutions, for instance salts of alkalis, alkaline earths, including magnesia and beryllium, aluminium, etc. Other substances are also suitable for instance other salts of alkaline earths, and generally any substances capable of producing on the cathode a precipitate lowering the reducing action. The aforesaid precipitate may be formed by a multitude of reactions, the nature of which is not yet definitely settled; it may be attributed to the electrolytic deposition of the basic metal of the salt at the cathode, the metal being liable to enter various reactions, causing for instance decom-

position of water and producing an insoluble 55 oxid or hydroxid at the cathode; moreover, the products generated at the cathode may react with ingredients of the electrolyte causing a precipitate on the cathode, etc. If desired this precipitate may be made more 60 effective by making it finer and uniformly dense by the addition of protective colloids, such as for instance, albumin, starch, gum-arabic, etc.

The use of a diaphragm which is usual in 65 such cases, led for many reasons to inconveniences; for instance the pressure of the bath was considerably increased, and the composition of the electrolyte modified by the separating action of the diaphragm. In 70 order to avoid this, it would be necessary to take special precautions which render the process more difficult. By applying the new process they are not necessary.

Inasmuch as the "substance capable of 75 producing a precipitate on the cathode" mentioned in the claims, includes the salts, or mixtures of the salts of the alkaline earths I refrain from further mentioning them specifically in the claims. 80

I claim:

1. The process of manufacturing alkali-perborate by electrolyzing a solution of an alkalicarbonate and of an alkaliborate, which comprises adding to the electrolyte a 85 substance capable of producing a precipitate on the cathode.

2. The process of manufacturing alkali-perborate by electrolyzing a solution of an alkalicarbonate and of an alkaliborate, 90 which comprises adding to the electrolyte a mixture of substances capable of producing a precipitate on the cathode.

3. The process of manufacturing alkali-perborate by electrolyzing a solution of an alkalicarbonate and of an alkaliborate, 95 which comprises adding to the electrolyte a substance containing chromium capable of producing a precipitate on the cathode.

4. The process of manufacturing alkali-perborate by electrolyzing a solution of an alkalicarbonate and of an alkaliborate, 100 which comprises adding chromic acid to the electrolyte.

5. The process of manufacturing alkali-perborate by electrolyzing a solution of an alkalicarbonate and of an alkaliborate, 105 which comprises adding to the electrolyte a

chromate of a base unable to decompose an alkali perborate.

6. The process of manufacturing alkali perborate by electrolyzing a solution of an alkalicarbonate and of an alkali borate which comprises adding to the electrolyte a mixture of a chromate and of a salt of an alkaline earth capable of producing a precipitate on the cathode.

10 7. The process of manufacturing alkali perborate by electrolyzing a solution of an alkalicarbonate and of an alkali borate, which comprises adding to the electrolyte a protective colloid and a substance capable of producing a precipitate on the cathode.

15 8. The process of manufacturing sodium perborate by electrolyzing a solution of soda

and borax, which comprises adding to the electrolyte a substance capable of producing a precipitate on the cathode.

9. The process of manufacturing sodium perborate by electrolyzing a solution of soda and borax, which comprises adding to the electrolyte a protective colloid and a substance capable of producing a precipitate on 25 the cathode.

In testimony whereof I have signed my name to this specification in the presence of two subscribing witnesses.

OTTO LIEBKNECHT.
